UNITED STATES PATENT OFFICE.

ROBERT L. MORRISON, OF NATHAN, TEXAS.

PLOW.

SPECIFICATION forming part of Letters Patent No. 664,570, dated December 25, 1900.

Application filed May 24, 1900. Serial No. 17,870. (No model.)

To all whom it may concern:

Be it known that I, ROBERT L. MORRISON, a citizen of the United States, residing at Nathan, in the county of Johnson and State of Texas, have invented certain new and useful Improvements in Plows, of which the following is a specification.

This invention relates to plows, and particularly to a plow having a land shoe or slide 10 hinged to the plow-point and fixed to the depending portion of the plow-beam.

The object of the invention is to provide a plow especially fitted for the bedding of cotton-land; and to effect this I employ right and 15 left moldboards, secure the plow-point to them, use novel and peculiar means for loosely connecting them to the plow-standard or the depending portion of the plow-beam, fix a land slide or shoe to the end of said portion 20 or standard, and hinge the shoe to the plow-point, so that the said hinge acts as a pivot for the free movement of the plow-point and moldboard up and down or vertically without lifting the shoe from the furrow except 25 in striking unusual obstructions, in which case the shoe is tilted backward or forward from the plow-handles, the shoe acting as a fulcrum, while the plow-point and moldboards hang loose on the hinge and are kept 30 in proper alinement by the slideable connection with the plow beam or extension.

In the accompanying drawings, forming part of this application, Figure 1 is a perspective view, partly broken away. Fig. 2 is a 35 longitudinal section. Fig. 3 is a perspective view of the bracket looking at the under side thereof. Fig. 4 is a perspective view of a modification.

The same numeral references denote the 40 same parts throughout the views of the drawings.

The plow-beam 1 has a depending portion or standard 2, to which is secured a V-clamp 3 for connecting the handles 4. To the end 45 of the standard 2 is fixed at 2^a a land slide or shoe 5, so that it is rigid with the plow-beam and projects considerably to the rear

thereof. The handles 4 are braced to the beam 1 by suitable rods 6.

The importance of my invention lies in the 50 novel and peculiar means for connecting the plow-point and moldboards together, so that the latter may slide on the plow-beam extension and the former may be hinged or pivoted to the land slide or shoe 5. This means consists of a bracket having wings 7 to suit the curvature of the moldboards 6^a and plow-point 7^a, to which they are secured by suitable screws or bolts 8 and 9, respectively, the top end of the said wings having rearwardly-projecting arms 10, which overlap and are loosely secured around the plow-beam extension or standard 2 by bolts 11. The bottom end of the bracket at the juncture of the wings 7 is provided with ears 12, through 65 which and the forward end of the shoe 5 a pivot-bolt 13 extends. These ears may be substituted by a U-shaped hanger 14, having holes 15 for bolting it to the bracket and plow-point, as shown in Fig. 4.

It is obvious that the bracket affords not only a simple, convenient, and inexpensive means of connecting the moldboards and plow-point together, but it connects the point pivotally with the shoe and makes a vertically-slidable connection between the moldboards, plow-beam, and shoe. The handles being secured to the standard or beam extension between the fixed point of the shoe and standard and the arms 10 permits the handles 80 to be operated directly upon the shoe and allows the said arms uninterrupted play.

Having thus described my invention, what I claim as new, and desire to secure by Letters Patent, is—

1. In a plow, the combination, with a shoe fixed to the standard or plow-beam extension, of the bracket connecting the plow-point with the moldboards and pivoted to the shoe, and having arms slidably connected to the said standard or extension.

2. In a plow, the combination, with a shoe fixed to the standard or depending portion of the plow-beam, of a bracket connecting the

plow-point and moldboards together, and having rearwardly-projecting top arms loosely surrounding the said beam portion, and bottom ears to which the forward end of the said

5 shoe is pivoted.

3. In a plow, the combination, with the shoe fixed to the depending end of the plow-beam, and the V-clamp carrying the plow-handles and secured adjacent to the said fixed point,

10 of the bracket secured to the moldboards and

plow-point, and having top arms free to slide on said beam above said clamp, and bottom ears pivoted to the forward end of the said shoe.

In witness whereof I hereunto set my hand 15
in the presence of two witnesses.

ROBERT L. MORRISON.
